UNITED STATES PATENT OFFICE

154,554

DESIGN FOR A TIE RACK

Saul Lipsitz, Chelsea, Mass.

Application August 1, 1947, Serial No. 140,668

Term of patent 14 years

(Cl. D33—8)

To all whom it may concern:

Be it known that I, Saul Lipsitz, a citizen of the United States of America, residing at Chelsea, in the county of Suffolk and State of Massachusetts, have invented a new, original, and ornamental Design for a Tie Rack, of which the following is a specification, reference being had to the accompanying drawing, forming a part thereof wherein:

Figure 1 is a view in side elevation of a tie rack, showing my new design.

Figure 2 is a top plan view thereof.

I claim:

The ornamental design for a tie rack, as shown.

SAUL LIPSITZ.
